UNITED STATES PATENT OFFICE.

OSCAR FREDRIK JÖNSSON, OF STOCKHOLM, SWEDEN.

AUTOMATIC STOP APPARATUS FOR MOTORS DRIVING DYNAMO-ELECTRIC MACHINES.

SPECIFICATION forming part of Letters Patent No. 326,223, dated September 15, 1885.

Application filed February 10, 1885. (No model.)

To all whom it may concern:

Be it known that I, OSCAR FREDRIK JÖNSSON, a subject of the King of Sweden, residing at Stockholm, Sweden, have invented certain new and useful Automatic Stop Apparatus for Motors Driving Dynamo-Electric Machines, of which the following is a specification.

The object of this invention is an automatic stop apparatus to be interposed in the circuit 10 of a dynamo-machine, near the motor, to prevent the destruction of the dynamo-machine when interruptions or short-circuitings occur by instantly stopping the motor.

The apparatus is represented in the annexed 15 drawing, which shows a side view of the stop apparatus.

The apparatus is interposed in the circuit of the dynamo-machine by connecting its pole-screws A and B in the main circuit. At the 20 pole-screw A the current divides and passes simultaneously through two electro-magnets, C and D, and joins again at E, and the whole passes through the insulated strips F and G and to the pole-screw B. The circuit between 25 the strips F and G is completed by each strip having on its end a piece, H, descending into a vessel, I, containing mercury. The vessel I is mounted on the top of a vertical bar, K. This bar passes through and is guided by two 30 ears, L, and is at its lower end provided with a plate, M, the edge of which comes against a screw-head, N, on the armature O of the electro-magnet D. This armature is held back by a spring, P, from the magnet, the spring being 35 sufficiently strong to overpower the attraction until the current has increased to such a degree that danger is imminent both to the dynamo-machine and the circuits. The armature of the electro-magnet C consists of a double-armed lever, Q, provided with metal 40 screws R in front of the poles of the electro-magnet, in order to diminish the effect of the residual magnetism. A hook, S, is provided in order to retain the lever in its position 45 when no current is passing through the apparatus. On the opposite end of the lever a weight, J, is suspended, and from the weight a string passes over pulleys to the wheel U, which is keyed onto the spindle of the stop- 50 valve of the motor in such a manner that the weight, when free, in falling closes the valve.

The apparatus works in the following manner: When the current passes through the electro-magnet C, the armature Q is attracted so that the hook S, which is not further wanted, becomes disengaged. If any interruption now occurs in the circuit the magnetism ceases instantly, the consequence of which is that the weight J depresses the shorter end of the lever Q and glides off, thus stopping the motor. 55 If this apparatus did not exist the dynamo-machine and the motor would, in the event of an interruption in the circuit, increase their rapidity in consequence of motive power being no longer transformed into electricity, and 60 owing to the great speed the machine might be damaged.

Another danger for the dynamo-machine may arise in the event of short-circuiting a portion of the main circuit. In such an event 70 the resistance diminishes and the power of the current increases, so that the insulation of the machine and the circuit may be destroyed. When with this arrangement short-circuiting has taken place, and consequently 75 the current has increased, the attractive power of the magnet D will likewise be increased, and the armature O is attracted and moves to its magnet, allowing the bar K, with its vessel of mercury I, to fall down and disconnect the strips F and G. The electro-magnet C then 80 loses its magnetism and the weight J falls down and stops the motor.

I claim—

Automatic stop apparatus for motors driving dynamo-machines, consisting of two electro-magnets, C and D, in the main circuit, acting each upon its lever-armature, in combination with a string and weight, J, strips F and G, and movable vessel I, which contains mercury and is controlled by one of the electro-magnets, the said stop apparatus effecting in 85 an automatic manner the stopping of the motor driving the dynamo-machine in the event of interruption of the circuit or short-circuiting, substantially as described.

OSCAR FREDRIK JÖNSSON.
